US0D1030891S

(12) **United States Design Patent** (10) **Patent No.:** **US D1,030,891 S**
(45) **Date of Patent:** **** Jun. 11, 2024**

(54) **REMOTE CONTROL FOR MARINE PROPULSION SYSTEM**

(71) Applicant: **Brunswick Corporation**, Mettawa, IL (US)

(72) Inventors: **Ryan C. Abellera**, Fond du Lac, WI (US); **Todd D. Dannenberg**, Fond du Lac, WI (US); **Philip Ma**, Greensboro, NC (US)

(73) Assignee: **Brunswick Corporation**, Mettawa, IL (US)

(**) Term: **15 Years**

(21) Appl. No.: **29/893,014**

(22) Filed: **May 24, 2023**

Related U.S. Application Data

(62) Division of application No. 29/852,032, filed on Sep. 2, 2022, now Pat. No. Des. 992,642, which is a division of application No. 29/757,012, filed on Nov. 2, 2020, now Pat. No. Des. 967,271.

CLAIM

The ornamental design for a remote control for marine propulsion system, as shown and described.

DESCRIPTION

FIG. 1 is a rear perspective view of a remote control for a marine propulsion system according to our new and ornamental design;

FIG. 2 is a side view thereof;

FIG. 3 is an opposite side view thereof;

FIG. 4 is a rear view thereof;

FIG. 5 is a front view thereof;

FIG. 6 is a top view thereof; and,

FIG. 7 is a bottom view thereof.

The broken lines illustrate the aspects of the remote control for a marine propulsion system that are not part of the claimed design.

1 Claim, 7 Drawing Sheets
